Application February 12, 1940, Serial No. 318,460

5 Claims. (Cl. 72—66)

This invention relates to precast concrete slabs.

One object of the invention is the provision of a concrete slab adapted for use in building construction, and having a high degree of strength and rigidity.

Another object of the invention is the provision of a precast concrete slab one surface of which has a very smooth finish so that it may be used to form a finished wall in a building without requiring additional surfacing.

Another object is the provision of a concrete slab the side portions of which are so formed as to provide grout receiving spaces when bottom portions of a series of similar slabs are arranged side by side in abutting contact with one another.

Another object is the provision of a precast concrete slab having longitudinally extending pretensioned reinforcing rods.

Another object is the provision of a precast concrete slab having longitudinal passages of large size as compared with the thickness of the slab and so arranged that the slab is of comparatively small weight but well adapted to resist very large bending loads.

Another object is the provision of a precast concrete slab having a prestressed reinforcing structure such that the slab lies substantially flat when supporting its own weight from points of support at opposite ends of the slab.

Another object is the provision of a series of slabs of the character mentioned, arranged side by side and rigidly connected together to provide a building floor.

Another object is the provision of a precast concrete reinforced slab adapted to be assembled side by side with adjacent similar slabs to form a strong building wall providing a finished ceiling of one chamber of the building, and a floor of another chamber.

Other objects and advantages of the invention will be apparent from the following description, the appended claims and the accompanying drawings.

In the drawings, in which the preferred embodiment of the invention has been illustrated in the form of precast reinforced concrete slabs of generally rectangular cross section, adapted for use in the construction of a building wall or roof,

Fig. 1 is a perspective view of a portion of a building floor formed from a series of precast concrete slabs, embodying the present invention;

Fig. 2 is a transverse sectional view through one of the slabs;

Fig. 3 is a section on the line 3—3 of Fig. 2;

Fig. 4 is a perspective view of a series of slabs arranged to provide a floor and a ceiling and showing the slabs in the course of assembly;

Fig. 5 is a top plan view of a portion of the slab series shown in Fig. 4;

Fig. 6 is a section on the line 6—6 of Fig. 5;

Fig. 7 is a side elevation showing the form in which the slabs may be cast, and showing the form support;

Fig. 8 is a transverse section of the form on the line 8—8 of Fig. 7;

Fig. 9 is an end view showing a portion of the form; and

Fig. 10 is a longitudinal section through a portion of the form, taken on the line 10—10 of Fig. 9.

20 Referring more particularly to the drawings, like parts being designated by the same reference numerals in the several views, 10, 11 and 12 designate portions of precast concrete reinforced slabs or beams, arranged side by side and sup-

25 ported at their opposite ends to provide a floor or roof of a building and to provide the ceiling of a room below the floor or roof. The slabs, as shown, are carried at one end on a flat level surface such as a leveling strip 13 arranged on a suitable foundation 14 of masonry or other material, the opposite ends of the slabs being carried in a similar manner.

Each of the slabs shown comprises a concrete body 16 of generally rectangular cross-sectional 30 form, having reinforcing rods 17, 18 and 19 ex-

35 tends longitudinally of the slab near its lower side, with additional reinforcing rods 20 and 21 preferably embedded in the concrete near the upper side of the slab. Longitudinal passages 22

40 of large diameter compared to the thickness of the slab extend longitudinally from one end of the slab to the other. The slab shown is twice as wide as it is thick, with two passages 22 that are of such diameter as to make the total void

45 of the order of from 40% to 50% of the entire slab. The slab is thus provided with strong arches connecting the upper and lower portions so that its strength is very great especially in resisting bending loads. The neutral axis of the

50 slab is quite close to the top of the passages 22, preferably just slightly below the top of the passages. The slab may be quite long, slabs of 22 feet or longer proving quite satisfactory in a construction in which the vertical slab thickness is 6 inches.

One side 24 of the slab is quite smooth. This is preferably the lower side which is also provided with smooth curves 25 at its edges, these curves merging with the side surfaces 26 which are adapted to be arranged in abutting relation with the corresponding portions of adjacent slabs. The top surface 27 of the slab is of somewhat less width than the bottom surface so that the upper side surfaces 28 of adjacent slabs are spaced apart to provide a channel, closed at the bottom by the lower portions of the slabs, in which grout may be poured in order that a series of the slabs may be held rigidly one to another. The side surfaces 28 are provided with longitudinally extending grooves 29 so that the hardened grout will be securely interlocked to the adjacent slabs and each slab will be rigidified against bending by the other slabs connected to it.

In assembling the slabs and before grouting the spaces between adjacent slabs, they may be pulled into flush relationship with one another at one or more points between their supported ends, in the manner more fully set forth in our copending application Serial No. 318,462, filed February 12, 1940, for Building construction. Since the supported ends rest on flat leveling strips 13, these end portions will be flush with one another but the several slabs may not be of exactly uniform strength and their middle portions may therefore be at different levels when first placed in position. To level the slabs at their middle or unsupported points, nuts 31 carried by bolts 32 may be placed in the channels between adjacent slabs, being applied from the ends of these channels. The bolts carry plates 34 which may be turned to extend transversely of the length of the slab as indicated by the dotted lines in Fig. 6 and as shown in the center of Fig. 5. A frame comprising angle irons 35 and 36 connected at their ends by connecting plate 37, see Fig. 5, may be moved down against the top of the slabs so as to extend transversely of the slab length, the width of the plates 34 being small enough so that they will be received between the angle iron webs during the positioning of the frame, and the plates 34 are then raised and turned to rest on the webs of the angle irons. The bolts 32 are then turned with a wrench so that one slab is pulled vertically with respect to another adjacent slab that might be at a slightly different level, as the nuts are brought tight against the upper parts of the grooves 29 of the slabs. All of the slabs may thus be brought to a flush relationship with one another.

After the slabs have been leveled and all of the bolts 32 tightened, the space between adjacent slabs may be filled with grout level with their upper surfaces and after the grout has hardened the bolts 32 are unscrewed, leaving the nuts 31 in place, and the angle iron frames are taken off. If desired, the threaded holes left in the concrete when the bolts 32 are removed may be filled with grout although they may remain if a wood flooring is to be applied to the upper surface of the slabs. The left-hand portion of Fig. 1 shows a wood flooring 38 laid on wood strips 39 secured by bolts 40 threaded to the threaded passages which are left when the bolts 32 are removed.

The concrete slabs are preferably cast in a form, shown in Figs. 7 to 10 inclusive, and in accordance with our copending application Serial No. 318,461, filed February 12, 1940, for Casting slabs. The form has the shape of an open top horizontally extending trough the internal shape and dimensions of which correspond to the slab

produced. The lower side of the trough is formed by a smooth metal plate 42 having upwardly turned side walls 43 providing smooth curved fillets 44 at each of the lower corners, which form the smooth curves 25 along the lower side edges of the slab. The opposite sides 45 and 46 of the form are so shaped as to provide the grout receiving spaces, and the grooves, at the opposite sides of the slab. The opposite ends of the form are closed by end plates 55, having holes 60 and 61 of a diameter corresponding to the size of the passages that are cored in the slabs. These holes 60 and 61 receive the ends of tubes 63 which are preferably inflatable rubber tubes of the character disclosed in the patent to Lindas No. 1,949,650. Such tubes, when inflated, expand uniformly in diameter throughout their effective length, and shorten in length at the same time. The tubes are applied and then subjected to sufficient pressure to bring the walls of the tubes against the holes 60 and 61 and the pressure supply is then cut off.

Before the tubes are applied to the form the reinforcing steel structure is first laid in place in the form, this structure comprising the reinforcing rods 17, 18 and 19 which act in tension in the finished product, and the additional longitudinally extending reinforcing rods 20 and 21 which are especially desirable for transportation purposes when the forms are carried in an inverted position. If desired the middle rod 18 may be substituted by a wiring conduit pipe and outlet box that may be embedded in the concrete so that the bottom of the box is even with the lower surface of the slab. The several reinforcing rods, which are so positioned as to be embedded in the concrete near the upper and lower surfaces of the slab and protected on all sides with concrete of sufficient thickness to give a satisfactory protection against fire, are interconnected to one another at spaced intervals along the length of the form by means of wires or stirrups 67, which define a rectangle having a cross sectional form corresponding to the sides of the rectangle defining the total cored area. Extending across the top of the form are a series of straps 68 adapted to be readily removed and applied, and having rod engaging hooks engageable with the rods 20 and 21 to pull them upwardly into their proper position, and also having locating pins 80 engaging the upper sides of the tubes 63 to position these tubes at the proper distance from the sides of the form and at a desired height in the form, since the tubes, being hollow, tend to rise in the concrete mixture applied to the form.

The rods 17, 18 and 19 are comparatively close to the bottom surface of the slab and thus act effectively in resisting bending loads when the slabs are supported at their opposite ends. These rods end in threaded lugs 82 having head portions 83 welded to the ends of the rods, and having threaded extensions 84, the plates 55 having openings located opposite the threaded extensions 84 and of such size as to receive tensioning nuts 85 adapted for threaded engagement with the extensions 84. The tension nuts 85 are tightened before pouring the concrete into the form, so as to stretch the rods and thus pretension them to give a predetermined initial elongation, the nuts 85 being turned by a suitable wrench to apply a known amount of torque in order that the required predetermined amount of pretension may be given to the rods. The tensioning nuts 85 are not unscrewed until after the concrete 75 poured into the form has set and created a secure

bond to the rods throughout their length. The head portions 83 prevent any possibility of the rods slipping with respect to the concrete with which they are bonded.

The rods are pretensioned to some point below their elastic limit, the degree of pretensioning preferably being such that the finished slabs, when supported at their opposite ends and carrying their own weight, will be prevented from sagging in their middle portions, and will extend substantially horizontally between the slab supports. With the rods under some predetermined initial tension the normal form of the slab is slightly bowed in a longitudinal direction when the slab rests on its side, the contracting force of the pretensioned rods curving the side 24 into a slightly concave shape and producing a corresponding convex curve along the surface 27. This curve is preferably such that when the slabs support their own weight they rest perfectly horizontally when supported at their opposite ends with the surfaces 27 uppermost, the rods at this time being under some very considerable tension even though the axis of the rods may be perfectly straight. The downward deflection of the slabs, when subjected to large loads is thus resisted by the rods to a far greater degree than the resistance exerted by rods that are normally untensioned. The slabs are therefore very rigid and offer great resistance to bending or sagging.

Before filling the form with concrete, those surfaces of the form to which the concrete mixture is applied are preferably first oiled so that the concrete, when set, can be readily separated from the metal parts of the form. The concrete mixture is poured or shoveled into the form until it comes level with the top of the form, the concrete mixture being a suitable mixture or mass to provide a hard strong compound formed by concretion or coalescence of the particles. A mixture of one part cement and five parts of a mixture of sand and gravel, thoroughly mixed together with water constitutes a very satisfactory mix. After the form is filled it is supported for vibratory movement and vibrated rapidly for a short time. The traps 68 are then removed, and the upper surface of the concrete mixture leveled off flush with the top of the form after the concrete has set, the tubes 63 are removed, the nuts 85 unscrewed and the form disassembled. When the nuts 85 are removed the threaded ends of the rods 17, 18 and 19 are accessible for use in connecting other parts to the ends of the slabs, if desired.

The vibratory movement imparted to the concrete mixture causes air bubbles to rise rapidly in the mixture and be eliminated, increasing the density and strength of the concrete slab produced due to air elimination especially from the bottom of the concrete mass. This increase of strength amounts to about 10% to 15% where the vibration is such as to eliminate about 90% of the air bubbles that would otherwise remain. The vibratory movement of the mixture causes the mixture to entirely fill all the crevices and come into intimate contact with all surfaces of the form, tubes, reinforcement, etc., resulting in a very smooth surface on those portions of the slab that are formed by engagement with the metal bottom. The lower surface of the finished slab will thus have a smoothness comparable to the smoothness of the smooth sheet metal plate which forms the lower part of the form as it will be substantially free of pits caused by air bubbles, and the curved lower corner portions 25 will

be very smooth so that the lower sides of the slabs may be used without additional surfacing to form the finished ceiling of a room. The need for lath and plaster is thus entirely eliminated and there is no possibility of the ceiling cracking or falling. For decoration purposes mere painting may be used. The upper sides 27 of the slabs have a flatness so that they may be used without additional covering or additional surface treatment, as a roof or floor, although the top surface may be ground smooth to show up the outlines of the stone portions employed in the mix, as indicated in the upper right portion of Fig. 1.

As already mentioned the longitudinal passages in the slabs are of large diameter. If they are made so large as to reduce the weight of the slab substantially in excess of 50% the slab strength will be adversely affected, and if made small enough to reduce the weight substantially less than 40% the increased weight of the concrete employed will also adversely affect the slab strength. Within the range of from 40% to 50% void space, however, the slab strength and rigidity will be a maximum. As one specific example of a slab construction that has proved quite satisfactory and of great strength, the slab has outside dimensions of 6 inches by 12 inches with two passages of $4\frac{1}{8}$ inches diameter spaced apart $\frac{3}{4}$ inch and spaced $\frac{1}{8}$ inch from the sides and $\frac{1}{8}$ inch from the top, three reinforcing rods of $\frac{1}{2}$ inch diameter spaced $\frac{1}{2}$ inch from the bottom being employed. Assuming a safe elastic limit for the steel rods of 20,000 pounds per square inch, and a safe compression strength of 1500 pounds per square inch for the concrete itself, the deflection produced by a uniformly distributed load of 150 pounds per square foot in a 14 foot span will be less than .46 inch. In such a slab the total cross sectional area of the passages will be slightly less than 50% of the cross sectional area of the entire slab.

While the article herein described constitutes a preferred embodiment of the invention it is to be understood that the invention is not limited to this precise article, and that changes may be made therein without departing from the scope of the invention which is defined in the appended claims.

What is claimed is:

1. A precast concrete slab comprising an elongated body of concrete generally rectangular in cross-section, of greater width than thickness and having a plurality of longitudinally extending cylindrical passages of such diameter compared with the slab thickness as to provide a total void of at least 40% and not substantially in excess of 50% of the slab section, the passages being located substantially closer to the bottom of the slab than to the top, the bottom portion of the slab having a greater width than the top, upper longitudinally extending reinforcement embedded in the upper portion of the slab, and lower longitudinally extending reinforcing rods embedded in the lower portion of the slab, such lower rods being pretensioned and of such cross sectional area as to assume substantially the entire tension forces due to live load, the cross sectional area of the pretensioned reinforcing rods and the diameter of the passages being so coordinated as to locate the neutral axis of the slab closely adjacent the tops of the passages.

2. A precast concrete slab comprising an elongated body of concrete generally rectangular in cross-section, having a width substantially twice its thickness and having two longitudinally ex-

tending cylindrical passages of such diameter compared with the slab thickness as to provide a total void of at least 40% and not substantially in excess of 50% of the slab section, the passages being located substantially closer to the bottom of the slab than to the top, the bottom portion of the slab having a greater width than the top, the upper side portions of the slab each having a recess extending longitudinally of the slab, upper longitudinally extending reinforcing rods embedded in the upper portion of the slab, and lower longitudinally extending reinforcing rods embedded in the lower portion of the slab, such lower rods being of such cross-sectional area as to assume substantially the entire tension forces due to live load and having such pretension as to provide a longitudinal upward bend between the slab ends of such extent that the slab is substantially straight when it supports its own weight from its opposite ends, the cross sectional area of the pretensioned lower rods and the diameter of the passages being so coordinated as to locate the neutral axis of the slab closely adjacent the tops of the passages.

3. A precast concrete slab comprising an elongated body of concrete generally rectangular in cross-section, of greater width than thickness and having a plurality of longitudinally extending cylindrical passages of such diameter compared with the slab thickness as to provide a total void of at least 40% and not substantially in excess of 50% of the slab section, the passages being located substantially closer to the bottom of the slab than to the top, the bottom portion of the slab having a greater width than the top and having a cast concrete surface of a smoothness comparable to that of a smooth metal plate with smooth rounded corner portions merging into the sides of the slab and entirely devoid of edges, the upper side portions of the slab each having a recess extending longitudinally of the slab, upper longitudinally extending reinforcement embedded in the upper portion of the slab, and lower longitudinally extending reinforcing rods embedded in the lower portion of the slab, such lower rods being pretensioned and of such cross-sectional area as to assume substantially the entire tension forces due to live load, the cross-sectional area of the pretensioned reinforcing rods and the diameter of the passages being so coordinated as to locate the neutral axis of the slab closely adjacent the tops of the passages.

4. A precast concrete slab comprising an elongated body of concrete generally rectangular in cross-section, having a depth substantially twice its thickness and having a pair of longitudinally extending cylindrical passages of such diameter compared with the slab thickness as to provide a total void of at least 40% and not substantially in excess of 50% of the slab section, the bottom portion of the slab having a greater width than the top, the passages being located substantially closer to the bottom of the slab than to the top, and the slab having a cast concrete lower surface of a smoothness comparable to that of a smooth metal plate, with smooth rounded corner portions merging into the sides of the slab and entirely devoid of edges, upper longitudinally extending reinforcement embedded in the upper portion of the slab, and lower longitudinally extending reinforcing rods embedded in the lower portion of the slab, said lower rods having such pretension as to provide a longitudinal upward bend between the slab ends when the slab is free of load, and said lower rods being of such cross sectional area as to assume substantially the entire tension forces due to live load, the cross-sectional area of the pretensioned reinforcing rods and the diameter of the passages being so coordinated as to locate the neutral axis of the slab closely adjacent the tops of the passages.
5. A precast concrete slab comprising an elongated body of concrete generally rectangular in cross-section, of greater width than thickness and having a plurality of longitudinally extending cylindrical passages of such diameter compared with the slab thickness as to provide a total void of at least 40% and not substantially in excess of 50% of the slab section, the passages being located substantially closer to the bottom of the slab than to the top, upper longitudinally extending reinforcement embedded in the upper portion of the slab, and lower longitudinally extending reinforcing rods embedded in the lower portion of the slab, such lower rods being pretensioned and of such cross-sectional area as to assume substantially the entire tension forces due to the live load, the cross sectional area of the pretensioned reinforcing rods and the diameter of the passages being so coordinated as to locate the neutral axis of the slab closely adjacent the tops of the passages.
